Universal Camera Corporation, New York, N. Y.,
a corporation of New York

Application February 14, 1945, Serial No. 117,947

Term of patent 14 years

(Cl. D57—1)

To all whom it may concern:

Be it known that I, George Kende, a citizen of the United States and a resident of Dobbs Ferry, county of Westchester, city and State of New York, with a post-office address c/o Universal Camera Co., 28 West 23rd Street, in the Borough of Manhattan, city and State of New York, have invented a new, original, and ornamental Design for Binoculars, of which the following is a specification, reference being had to

the accompanying drawing, forming part thereof, in which

Fig. 1 is a front elevation of binoculars showing my new design.

Fig. 2 is a plan view of the same looking upwardly.

I claim:

The ornamental design for binocular, as shown.

GEORGE KENDE.
